his Atty.

UNITED STATES PATENT OFFICE.

MARSHALL D. GIBSON, OF WEBSTER GROVES, MISSOURI.

CHURN.

1,415,334.

Specification of Letters Patent. Patented May 9, 1922.

Application filed September 23, 1918. Serial No. 255,246.

To all whom it may concern:

Be it known that I, MARSHALL D. GIBSON, a citizen of the United States, residing in the city of Webster Groves, in the county 5 of St. Louis and State of Missouri, have invented a new and useful Improvement in Churns, of which the following is a specification.

This invention relates to churning, and has 10 reference more particularly to a novel dasher or agitator construction therefor. It has for its objects to produce a simple, inexpensive and efficient device of this character for use as a kitchen utensil in churning, 15 mixing and whipping cream, eggs, glucose, and other materials or substances; and to attain certain advantages as will herein-after more fully appear.

The invention consists essentially in a 20 novel combination of vacuum cup and beaters with means for imparting a rapid reciprocation and simultaneous rotation thereof; and in the parts and combinations and arrangements of parts hereinafter described and claimed.

In the accompanying drawing illustrating an approved embodiment of the invention,—

Figure 1 is a view, partly in vertical section, showing the complete device;

Figure 2 is a top view of the closure for 30 the container detached;

Figure 3 is an inverted end view of the vacuum cup;

Figure 4 is a fragmentary view, partly in 35 section, showing a modification of the vacuum cup; and

Figure 5 is an inverted end view of the vacuum cup, showing a modified form of beater.

Referring now to the drawing, the numeral 1 designates the receptacle or container 40 having a removable closure 2, which may be of any desirable or approved kind or character, but is shown as an ordinary commercial glass jar having a screw-cap and commonly known as a Mason jar.

The dasher or agitator comprises a vacuum cup 3, which, preferably, is either spherical or conoidal, as respectively shown 50 in Figures 1 and 4.

Around the edge of the cup is a series of blades or wings 4 which are preferably made integral therewith. As shown, they have reduced neck portions 5 which are 55 twisted to present the widened end portions

inclinedly (see Figure 3) so that the substance being acted upon in the container is thrown inward, towards the center, when the cup is rotated in the one direction, and outward in the other direction. These 60 blades are preferably given an ogee or reverse curvature, as at 6, 7, as shown in Figure 3, or they may be straight as shown in Figure 5. Also, it is preferable to have the blades extend well inward close to the center 65 of the cup, but a relatively shorter distance outward from the circumference thereof.

Owing to the peculiar combination of vacuum cup and blades a rapid and thorough aeration and mixing of the substance is accomplished. On the down stroke 70 of the dasher air is carried forcibly into the mass with compression within the cup and released as the cup is moved upward, while at the same time the agitator blades or 75 beaters are acting to stir the mass beneath and about the cup. Therefore, in addition to the aerating effect due to the endwise reciprocation of the cup, a complete agitation is attained by imparting a simultaneous 80 rotation, first in the one direction and then oppositely, during each reciprocation; the result being to quickly lighten and froth the mass.

As a simple means of actuation, the cup 85 is fixed on the end of a screw 8 which works through an aperture 10 in the cap 2 and has a handle 9 swiveled on its outer end. As shown, the screw comprises a flat bar which is twisted regularly throughout its length 90 to provide the necessary convolutions or flights, and the aperture 10 through which the screw works is in the form of a slot. Hence, by grasping the handle and forcing the screw endwise through the slot, the 95 simultaneous endwise reciprocation and rotation of the dasher is brought about.

The slot 10 may be provided in the cap proper, but to utilize the ordinary commercial caps which are sometimes of relatively 100 soft metal and will not withstand the wear of the screw thereon, an adapter in the form of a supplemental, relatively hard metal plate 11 may be attached thereto. As shown in Figures 1 and 2, this plate is provided 105 with marginal lugs or prongs 12 which are projected through corresponding apertures provided therefor and rebent over upon the outer face of the cap, the slot 10 being located in the center of the plate and coincid- 110

ing with a circular aperture 13 in the cap of sufficient size to make clearance for the screw.

As hereinbefore stated, the invention comprehends broadly the combination of vacuum cup and beaters. Obviously, therefore, the device admits of considerable modification without departing from the spirit of the invention, and is not limited to the specific construction and arrangement shown in the drawing.

What is claimed is:

1. In a device of the character described, a dasher comprising an inverted cup having an unobstructed interior chamber and a series of blades depending from the edge thereof.

2. In a device of the character described, a dasher comprising an inverted cup having agitator blades depending from and extending across the margin thereof and in inclined relation to the perimeter.

3. In a device of the character described, a dasher comprising an inverted cup having a series of marginal blades disposed inclinedly in a circular arrangement and extending in proximity to the axis of the cup. 25

4. In a device of the character described, a dasher comprising an inverted cup having a series of blades disposed inclinedly across 30 the edge thereof, said blades extending at one side beyond the circumference of the cup and at their other side in proximity to the axis of the cup.

5. In a device of the character described, 35 a dasher comprising an inverted cup having a series of blades depending from and extending on opposite sides of the margin thereof and disposed inclinedly in circular arrangement, said blades being formed with 40 reversely curved inner and outer portions.

Signed this 17th day of September, 1918,
at St. Louis, Missouri.

MARSHALL D. GIBSON.
